(57) CLAIM

The ornamental design for a wipes container, as shown and described.

DESCRIPTION

FIG. 1 is a perspective view of a wipes container showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is top plan view thereof; and,

FIG. 7 is a bottom plan view thereof.

The broken-line disclosure in the views is understood to represent portions of the article in which the claimed design is embodied, but which form no part of the claimed design, and where a broken line abuts a claimed surface, it is understood to represent an unclaimed boundary between claimed and unclaimed surfaces.
